UNITED STATES PATENT OFFICE

FRANK MORGAN HOWE, OF NEW YORK, N. Y.

DENTAL APPLIANCE

Application filed February 25, 1929. Serial No. 342,380.

This invention relates in general to a tooth brush and apparatus by which a continuous spray or stream of fluid is supplied to the brush and discharged therefrom into the mouth. The invention is concerned more particularly with a dental brush adapted to be used with a powder, a paste, or a liquid dentifrice. The apparatus specifically illustrated and described herein is adapted to be used as a dental apparatus but it is to be understood that with slight modifications, it may be used for other analogous purposes as for example, sterilizing brushes used for cleansing bottles and similar containers, shampoo brushes, etc.

The method of cleansing teeth in vogue at the present time which comprises brushing the teeth with a more or less insanitary bristle brush to which the dentifrice is usually applied, in the form of a paste or a powder, causes abrasion of the teeth as well as injury to the soft tissues of the mouth, injury to the enamel of the teeth by continuous use, and in many instances, will perforate the enamel and enter the dentine. Even where the ordinary bristle tooth brush is used solely with a liquid dentifrice the enamel of the teeth is abraded by the rubbing action of the bristles on the teeth.

I have found that a spray, jet or stream of water or other liquid traveling at a relatively high velocity is very effective in removing food deposits and substances injurious to teeth. The spray or jet may be used without causing injury to the delicate tissues of the mouth. Applying a spray or jet of medicated liquid is often most beneficial. If a fine stream of a liquid or spray be used in conjunction with a suitable brush the teeth can be cleaned more efficiently and rapidly than can be done at the present time with the ordinary bristle tooth brushes having dentifrices applied thereto in the form of a paste or powder. In this connection, I prefer to use a detachable rubber brush having projections preferably formed integral with the body of the brush and made readily detachable from the handle or carrier therefor. Such a brush may be easily sterilized before and after use, thereby eliminating the danger of infection of the delicate tissues of the mouth. The pro-

jections may take various forms as indicated in the drawings.

The principal object of the present invention therefore is to provide brushes adapted to be supplied with continuous sprays or jets of liquid for cleaning purposes especially for cleaning the teeth and soft tissues of the mouth.

Another object of the invention is to provide a fountain brush having a fluid supply container which also serves as the handle for the brush.

In general the apparatus embodying a preferred form of the present invention comprises a fluid supply container having tubes connected therewith, one of which is normally immersed in the liquid in the container and the other extends from the container and is connected to a discharge nozzle preferably positioned so as to discharge a spray or jet of liquid through the brush and past the bristles or other projections of the brush. An air supply tube is adapted to force the liquid from the container and through the discharge nozzle. The air supply is preferably furnished through a motor driven pump such as described and illustrated in my Patent No. 1,555,287, granted September 29, 1925, or any other device in the nature of a light-weight portable apparatus designed to supply air under pressure.

The invention will be better understood from the following description and the accompanying drawings in which

Fig. 1 is a pictorial representation of an individual cleaning his teeth holding in one hand the dental cleaning brush described herein and in the other hand a switch for controlling the motor driven pump supplying liquid or air pressure to the brush.

Fig. 2 is a plan view of a preferred form of the dental cleaning brush in which a spray or atomized stream of liquid is discharged from the brush.

Fig. 3 is a similar side elevation of the brush shown in Fig. 2.

Fig. 4 is a view of a brush having a contact surface of sponge rubber.

Figs. 5 and 6 are side and end views of a

brush having a contact portion consisting of a flexible rib.

Fig. 7 is a side elevation of another form of dental cleansing brush in which a solid jet of cleansing or medicated fluid is discharged from the brush.

Fig. 8 is a partial plan view of the brush shown in Fig. 7, and

Fig. 9 is a diagrammatical representation of a dental cleaning system in which the liquid dentrifice container is separated from the brush proper.

Figs. 1, 2 and 3 illustrate a preferred form of my dental appliances.

In the drawings the numeral 1 represents a container for the supply of liquid dentrifice or other fluid to be used in the brush. The container 1 is preferably of cylindrical or any convenient form adapted to be grasped by the hand of the user so as to serve as the handle for the brush.

The device illustrated in Figs. 2 and 3 is provided with two outlet tubes extending from the cap 10 and is adapted to supply a fine spray of liquid through the discharge nozzle 11. In this form of the device a tubing 12 extends from the interior of the container as shown to the discharge nozzle 11. Another tube 13 extends from the discharge nozzle 11 to the cap 10 and communicates with the interior of the container and has its end in alignment with the discharge end of the air tube 14.

For convenience in holding the cleaning brush, the container 1 may have formed therein a longitudinal groove adapted to accommodate the tube 8 so that the same will lie flush or nearly so with the exterior surface of the container thereby permitting the individual to hold the tooth brush securely and conveniently. The tube 8 is preferably held in position in the groove by means of a suitable clamp or clip 9 which encircles the container 1.

In the device as shown in Figs. 7 and 8, the open end of the container 1 is preferably provided with a metal cap 2 which may be screwed into the container so as to form an airtight joint. A piece of metallic tubing 3 extends through the cap 2 and substantially the full length of the container 1 as shown more clearly in Fig. 7. The end of the tube 3 in the container 1 is preferably bent as indicated at 4, so that the end thereof will be immersed in the liquid in the container when the latter is in the horizontal position shown in Fig. 1 and there is but a very limited supply of liquid in the container. The other end of the tube 3 is provided with a discharge nozzle 5, having a tapering outlet as shown more clearly in Fig. 8. A rubber or bristle brush 6 is mounted on the discharge nozzle 5 as shown in Fig. 8 and is fastened to the tube 3 by means of easily detachable clamps 7.

Air is supplied to the interior of the con-

tainer through a tube 8 so as to displace the stream of liquid from the container through the tube 3 and the discharge nozzle 5. The tube 8 is connected with suitable air compressing apparatus such as is described in my prior patent referred to above.

When it is desired to remove the cap 2 from the container for any purpose such as to pour in liquid, the tube 8 is disconnected from the air supplying apparatus, and partly released from the longitudinal groove in the side of the container 1 so that the cap 2 may be unscrewed from the container. The cap 10 has a hole 15 permitting the entry of air to the container.

When air is supplied through the tubing 14, it flows through the tube 13 and is discharged through the nozzle 11. The flow of air through the tube 13 tends to produce a partial vacuum in the container above the level of the liquid therein. Atmospheric air rushes through the hole 15 in the cap and displaces the liquid in the container through the tube 12 and through the discharge nozzle 11. The ends of the tubes 12 and 13 are provided with hollow trunnions 16 which support the discharge nozzle 11 and through which the liquid and air flow to the nozzle. The discharge of liquid and air simultaneously through the nozzle 11 causes the liquid to be atomized as it will be readily understood by those skilled in the art. This constitutes one form of a spraying or atomizing device, other forms being well known to the dental art and such may be used instead of the form described and to which a brush may be easily attached.

A brush 6, preferably of rubber or bristle, is mounted on the discharge nozzle and is held in position by means of the quickly detachable clamp or clip 18 extending across the tubes 12 and 13.

Other types of brushes may be used as illustrated in Figs. 4, 5 and 6. In Fig. 4, the contact portion is shown as being made of sponge rubber while in Figs. 5 and 6 the contact portion 17 is in the form of a central flexible rib having transverse slits and a central recess for the nozzle 11.

In the system illustrated in Fig. 9, the liquid supply container 19 does not form the handle of the cleaning brush as in the forms of devices shown in Figs. 2 and 7 but is mounted upon a shelf 20 located in a convenient place. The discharge nozzle 21 associated with the brush 22 is supplied with a stream of liquid which flows through the tube 23 communicating with the container 19 as illustrated. A handle 24 is provided and the tubing 23 extends therethrough as shown. Air is supplied to the container 19 through the tube 25 which is connected to the motor driven pump 26 operated from a wall outlet 27 as illustrated. The action of the pump 26 is con-

trolled by the switch 28 held by the hand of individual.

Having thus illustrated and described these specific embodiments of my invention, I do not wish to be understood as being limited to the details set forth for the construction and arrangement of parts may be altered as the occasion requires or the construction of the apparatus may be otherwise modified by those skilled in the art without departing from the spirit and scope of my invention as set forth in the appended claims.

What is claimed and desired to be protected by Letters Patent is:

15 1. A cleansing apparatus comprising, a fluid discharge nozzle, a brush combined with said nozzle, a fluid supply container adapted to have fluid ejected therefrom by air pressure, a fluid delivery tube connecting said 20 container with said nozzle, an automatic pumping device located at a distance from said container for supplying fluid under pressure to said nozzle, a flexible tube connecting said pumping device with said container, 25 a power control means for said pumping device and adapted to be operated while said brush is being used.

2. Dental cleansing apparatus comprising, a liquid discharge nozzle, a brush associated 30 with said nozzle, a liquid supply container adapted to serve as the handle for said brush and adapted to have a liquid ejected therefrom by air under pressure, a liquid delivery tubing connecting said container with said 35 discharge nozzle, an air supply tubing communicating with said nozzle, automatic means for causing air under pressure to flow through the last named tubing.

3. In dental cleansing apparatus having a 40 liquid supply container adapted to serve as a handle for a liquid discharge nozzle, the improvement which comprises providing the wall of said container with a longitudinal groove, a removable tube located in said 45 groove, and connecting said container with said discharge nozzle, and resilient means for holding said tube in said groove.

FRANK MORGAN HOWE.
